ADDRESS-PRINTING MACHINE

Joseph Krell, Berlin-Zehlendorf, Germany

Application August 24, 1933, Serial No. 686,610
In Germany September 2, 1932

3 Claims. (Cl. 101—58)

My invention relates to address-printing machines, and more particularly to machines of the kind described in my prior U. S. Patent 1,968,153, July 31, 1934, for "Address-printing machines".

5 In this machine, a perforated control chart is placed on a support so that the chart and the support move as a unit, and the operation of the machine with respect to the printing or skipping of its printing plates is controlled by the chart.

10 It is an object of my present invention to improve a machine of this type.

Means for selecting, i. e., selectively printing and skipping the printing plates as they are fed through the machine in sequence, by means of 15 perforated control members are old. In one type of selector, a circular control disk or master disk is placed on a rotating carrier which is connected to a source of electric energy and operated from the mechanism of the printing machine, as described in U. S. Patent 1,257,480, to Griswold, February 26, 1918, for "Selector printing mechanism". In the other type which is described in my above 20 said prior patent, the perforated control chart is placed on a drum which is connected to the source of electric energy.

25 In Griswold's mechanism, a fixed spring contact which is connected to the other terminal of the source of energy, cooperates with the master disk to make contact through its holes. In the machine described in my said prior patent, a scanning member which is connected to the other terminal of the source, moves along the drum and is fed for the pitch of two holes in the chart for 30 every operation of the drum.

35 Both types of selectors have serious drawbacks. In Griswold's mechanism, only a single circular row of perforations can be made in the master disk, unless the spring contact is movable. In this case, however, the perforations must be arranged in several circles and this is so confusing to the operator that it is hardly possible to operate with such a disk. Another drawback is that the number of perforations which can be made in a chart of given diameter, is limited.

40 In the machine described in my said prior patent, with a drum of large diameter, on which the control chart is placed, the device for perforating the chart at any desired point is rather complicated on account of the large width of the chart.

45 Another drawback is that extra means, such as pins and a straight-edge, are required for fixing the chart on the drum, and that the operation of such extra means is tedious. Still another difficulty is that the length of the chart must conform to very exact limits while the hygroscopic

properties of paper or cardboard cause variations of its length, and finally the selector is very complicated, particularly on account of the movable scanning member.

5 With the object of my present invention in mind, I so design the selector that it operates with a control strip instead of a disk or a chart of predetermined length. The strip is comparatively narrow and its perforations, or rather, the points where perforations can be made, are arranged in 10 rows transversely to the sides of the strip. The disposition is so lucid that the strip is punched at any desired point with a normal hand punch without the slightest difficulty.

15 The selector is fitted with fixed scanning members for making contact with the support or drum through the holes of the strip. The support or drum has means for moving a control strip past the support and past the scanning members, as against the machine in which the control chart 20 is fixed to the drum as described in my said prior patent. Such means may be pins on the drum which engage in holes of the strip, like film-feeding sprockets. The support or drum is fed from the printing mechanism of the machine intermittently in conformity with the pitch of the rows of 25 holes in the strip. In this manner, the rows are fed intermittently through between the scanning members and the support or drum.

30 A circuit is connected to the support and to a control magnet for the printing mechanism of the machine, and is made when one of the scanning members contacts with the support through one of the holes of the strip. Means are provided for successively connecting the individual 35 scanning members to the circuit of the control magnet.

35 The width of the scanning device formed by the individual scanning members is preferably equal to the transverse row of punching points, and the number of the members is equal to that of the points per row, so that, if every row has ten points, the scanning device has ten scanning members. Means are preferably provided for cutting the individual members into the circuit by which 40 they are connected to the said source of energy, in sequence.

45 In a preferred embodiment of my invention, the support for the control strip is a drum of 50 conducting material with a row of strip-feeding pins at either end, like a film-feeding sprocket. Its diameter is small, and it is free to turn on a shaft which, upon every forward movement of the printing plates, is turned through a given angle from the mechanism of the address-printing 55

machine. In another embodiment, the support is a strip of conducting material in a drum of insulating material.

The individual members of the scanning device are insulated from each other and are cut in successively by the partial rotations of the shaft on which the drum is free to turn. When a row has been scanned the drum is turned through the pitch of two transverse rows by suitable mechanism, and the scanning members are now ready for scanning the next row.

In the accompanying drawings, a selector of the first type referred to, with a drum of conducting material, and a selector of the second type referred to, with a drum of insulating material, and a strip of conducting material in the drum, both embodying my invention are illustrated diagrammatically by way of example.

In the drawings:

20 Figs. 1 to 7 illustrate the first, and Figs. 8 and 9 illustrate the second type.

More particularly, Fig. 1 is a perspective illustration showing a portion of a machine to which the selector of the first type is fitted,

25 Fig. 2 is a perspective illustration, drawn to a larger scale, of the selector, viewed from the rear in Fig. 1 and showing the selector ready for the reception of a fresh control strip,

Fig. 3 is an elevation of the selector, in axial 30 section for the major portion,

Fig. 4 is a section on the line IV—IV in Fig. 3,

Fig. 5 is an end elevation of the selector, viewed in the direction of the arrow V in Fig. 3, and partly broken open,

35 Fig. 6 shows a control strip, and

Fig. 7 is a diagram of connections.

The selector of the first type has ten individual members on its scanning device, and a drum of conducting material.

40 Fig. 8 is an elevation, and

Fig. 9 is a diagram showing the selector of the second type which has a single scanning member, and a drum of insulating material, with a conducting strip inserted therein for cooperation 45 with the scanning member.

Referring now to the drawings, and first to Figs. 1 to 7, the address-printing machine to whose table 1 the bracket 1 of the selector is secured by screws or the like, may be of any 50 suitable type and will not be described in detail, as it is no part of the present invention. Its printing arm 2 which is mounted to rock about a pivot extending in parallel to one of the longitudinal sides of the table 1, is operated by any 55 suitable means, not shown, to alternately bring down the printing platen 6 at its end for printing a plate 4, and for raising the platen from the table when the next printing plate is moved to the printing station. The printing plates 4 are 60 piled in a cage 3 on the table, and the lowermost plate of the pile is engaged by a feed slide 5 and pushed toward the printing station below the platen 6, along a track in the table 1. The system 65 of links and levers by which the printing arm 2 and the feed slide 5 are connected, is shown diagrammatically and in dotted lines at A. The printing arm 2 and the feed slide 5 cooperate in such manner that the feed slide presents every plate 4 at the printing station when the platen 70 6 descends.

The printing platen 6 is controlled for printing and skipping the plates by a system of links and levers B on the printing arm, and a control magnet St, Fig. 7. The cooperation of the control magnet with the platen 6 is also old. The system

B moves with the printing arm 2 without influencing the platen 6 so that the platen is not moved into active position, and the plates 4 at the printing station are skipped, unless the control magnet St is excited by the selector under the control of the strip 48, as will be described. If this occurs, the control magnet attracts its armature (not shown) and arrests the system B at its free or lower end. The platen 6 is now advanced by the cooperation of the rocking arm 2 10 with the partly arrested system B, and the plate 4 which is at the printing station at the time, is printed.

In a machine having the selector according to my invention, the printing plates or other printing members are not equipped with means such as projections, depressions or the like, and the machine is without the multiple switch which in machines whose printing plates have the said means, is provided for exciting the control magnet St, the magnet being operated by the selector scanning the strip 48.

Mounted to rotate in the selector bracket 1 is a shaft 8 on which a feeding drum is free to turn. The barrel 9 of the drum is of electrically conducting material, normally metal, and is mounted on the shaft 8 by two end plates 10 and 11 of insulating material. The barrel is equipped with two rows of pins 12 at opposite ends, for engaging in the sprocket holes 49 of the strip 48. Keyed on the shaft 8 near the inner end plate 10 of the drum 9 is a ratchet wheel 13 which is operated by a ratchet pawl 14 on a lever 15, Fig. 4. The lever is pivoted in the bracket 1 at 16 and equipped with a spring 17 for holding the pawl 14 in the teeth of 35 the ratchet wheel 13. The lever normally bears on a stop 20 but is connected to a Bowden cable or the like 21 at its free end. The cable 21 is operatively connected to any part of the printing mechanism, for instance, the system A, and 40 raises the free end of the lever 15 when the feed slide 5 advances. The movement of the lever 15 in the direction of arrow 18 effects a partial rotation of shaft 8 in the direction of arrow 19. The rotation of the shaft 8 is transmitted to the drum 45 9 by a spur gear 35 at the side of the outer end plate 11 which is connected to the end plate by rivets or the like. The spur gear 35 meshes with a pinion 36 on a lay shaft 37. All teeth of pinion 36 are as long as required for cooperation with the 50 teeth of spur gear 35, but every second tooth of the pinion is elongated. In Fig. 3, 36a are the short teeth whose length is equal to the length of the teeth of spur gear 35, and 36b are the elongated teeth. Keyed on the end of shaft 8 55 which projects beyond the spur gear 35 is a knob or handle 38 which on its perimeter, at 39, bears the numerals 1 to 10, as best seen in Fig. 2, and is knurled at 38a for facilitating the manipulation which will be described. The knob or handle has a single tooth 38b for cooperation with the elongated teeth 36b of pinion 36, and therefore will be termed the "single-tooth gear".

The ratchet wheel 13 by which the shaft 8 is rotated intermittently, and the single-tooth gear 65 38, are so related that while one of the rows on the strip is being scanned, the shaft 8 moves idly with respect to the drum, while performing certain switching operations, as will be described, until the row has been finished, whereupon the 70 single tooth 38b of gear 38, through pinion 36 and spur gear 35, feeds the drum for the subsequent row.

A disk 22 of insulating material is secured on the inner end of the shaft 8 to which, by screws 75

23, an annular spring 24 is secured. The spring supports an outer contacting block 25 and an inner contacting block 26.

The outer contacting block 25 cooperates with 5 ten contacting bosses 30 on a hollow support 28 of insulating material which is fixed to the inner end wall of the bracket 7. The inner contacting block 26 is in permanent contact with an annular contacting member 27, also on the hollow support 28.

A rod 40 projects outwardly from the inner end wall of the bracket 7, and two frames are mounted to oscillate on the rod. Each frame has two curved side arms 41, 42 and 41', 42', respectively, 15 as best seen in Fig. 2, and the free ends of the arms are connected by stays 43. Rollers 44 which are grooved so as to clear the pins 12 on the drum 9, are mounted to rotate on the stays 43. The frames are equipped with intermediate stays 430 20 which project beyond the arms 41 and 41' and are connected by a spring 45 which tends to pull the arms toward the drum 9. The arms 42 and 42' are equipped with stops 46 and a check 47 is provided on the end wall of the bracket 7 for 25 limiting the upward movement of the two frames. In the position illustrated in Fig. 2, the arms are in their topmost position and the spring is above the rod 40 so that its pull applies the stops 46 to the check 47. In this position, the selector is 30 ready for the reception of a strip 48. When the strip has been placed on the drum 9, the frames are turned down and the pull of the spring 45 now applies the rollers 44 to the strip.

Mounted on the stay 430 of the frame 41', 42' is 35 the scanning device 311 with the scanning members 31. The scanning members or contact brushes 31 are mounted side by side on the device 311, and insulated from each other. Their free ends bear on the drum 9 when the frames 41, 42 40 and 41', 42' have been turned down, and there is no strip 48 on the drum.

A double-armed contacting spring 32 is mounted on a pin 33, the free ends of the spring bearing on the drum 9 outside the row of pins 12 45 at its inner end. The pin 33 is insulated from the bracket 7, Fig. 3.

The connections of the selector, the control magnet St, etc., will now be described with reference to Fig. 7. In this diagram, the ten contacting bosses 30 and the drum 9 are shown with two parallel axes for the sake of clearer illustration, and the axes are connected by gearing 98, 99. The bosses are marked with the numerals I to X. The source of electric energy, here shown as a 50 system with a positive wire or terminal P, and a negative wire or terminal N, is connected to the inner contacting block 26 through a wire 29 and the annular member 27, as also shown in Fig. 3. The annular spring 24, with its outer contact 25, 55 is here shown as a switch which successively connects the bosses 30 to the inner block 26. The bosses 30 are connected to the scanning members 31 through ten wires which are housed in a tube 310, as best seen in Fig. 2. The spring 32 on the pin 33 whose ends make contact with the drum 9, as shown in Figs. 3 and 5, is connected to the negative wire N through a manually operated switch 53, the coil of the control magnet St, and a wire 34. A switch known as a "machine switch" 60 may be provided in the wire 34 intermediate the control magnet St and the negative wire N at 55, this switch being closed automatically by the mechanism of the printing machine before the selector is operated.

65 34' is a shunt from the wire 34 in which is ar-

ranged a relay 54 with an armature 57. The armature is connected to the positive wire P by a wire 56 and controls a contact to which a contacting point 58 for the switch 53 is connected.

A wire 59 is connected to one of the bosses 30, 5 for instance, the boss X as shown, and to the wire 34 through a wire 61 and across the resistance 60. 64 is another resistance which is also connected to the wire 61 at one end, and to the positive terminal P at its other end, through a wire 10 62 and a switch 63. The last-described connection serves for checking the synchronous operation of the printing plates 4 and the strip 48. A relay 65 which is connected to the wires 59 and 15 62, arrests the machine when the synchronous operation is disturbed, as will be described below.

The wires 34, 59 and 29 are housed in a tube 290, Figs. 2, 3 and 5.

Referring now to Fig. 6, this shows a preferred control strip 48. The strip which may be made 20 of any suitable material, as described above, and is preferably of thin cardboard, has two parallel rows of sprocket holes 49 along its sides for the pins 12 on the drum 9 to engage in. With the exception of its ends, the strip is printed with a 25 great number of parallel transverse rows at ten punching points per row. The punching points 50 may be perforated by a normal punching tool, or any other suitable means. The holes may be of any desired form, for instance, circular. In order to facilitate the punching of the strip transverse lines 51 are arranged on the strip after a given number of rows, in the present instance, after every tenth row, and the lines are marked with the total number of punching points in the 30 preceding rows, such as 100 after the tenth row, etc. A mark 52 is provided near the upper end of the strip, for a purpose which will be described. Any data may be written or printed on the ends of the strip 48 beyond the rows of punching points 35 50.

Obviously, the strip may be an endless band, or 40 may be made into an endless band by connecting its ends by pasting or other suitable means. In this case, another drum must be provided below 45 the drum 9, for guiding the endless band. This other drum is not shown.

Instead of a drum as illustrated, I may provide 50 another support for the strip, for instance, a flat plate of conducting material (not shown) past 55 which the strip is conducted stepwise and scanned by the members 31, or any other suitable means, making contact with the support through the holes in the strip.

For inserting the strip 48, the frames 41, 42 55 and 41', 42' are turned up as shown in Fig. 2, until the stops 46 engage the check 47 and the strip is now placed on the pins 12 of the drum with its sprocket holes 49. Marks 66 are on the drum, and the strip 48 should be so inserted that its mark 52 is in line with the topmost mark 66', Fig. 1. In this figure, the drum has moved beyond its initial position, and the marks 52 and 66' are out of register. The single-tooth gear 38 on the shaft 8 is turned to move its numeral "10" 60 into line with the mark 52 on the strip 48, in which position the single tooth 38b of the gear begins to engage the pinion 36 by which the gear 38 and the gear 35 on the drum 9 are connected as described above. The frames on the rod 40 are 65 now turned down. Their rollers 44 bear on the strip 48 under the pressure of spring 45 and the free ends of the scanning members 31 are slightly 70 in advance of the first row 50 on the strip 48.

75 It will appear that the insertion of the strip is 75

much facilitated and performed in a shorter time, than in the machine according to my said prior patent.

The operation of my selector is as follows:

- 5 Assume that at the beginning of the operation the boss 30 which bears the numeral "I" in Fig. 7, is connected to the wire 29 as shown. This connects the first scanning member, at the right-hand end of the drum 9, also to the wire 29, 10 and to the positive wire P. When the first printing plate 4 arrives at the printing station, the Bowden cable 21 raises the lever 15 and the shaft 8 is turned through an angle which corresponds to one tooth of the ratchet wheel 13. The partial rotation of the shaft 8 is transmitted to the drum 9 by the gearing 38, 36, 35 and the drum now presents the first row of punching points 50 to the scanning members 31. The rotation of the shaft 8 causes the outer contact 25 on the spring 24 to engage the boss 30 (I) and the first scanning member 31 is now in the circuit 29—9—34 from P to N, Fig. 7. If there is a hole at the first point (I) of the first row, the circuit is made through the scanning member and the drum and the plate at the station is printed. If there is no hole, the plate is skipped. Now, the second boss 30 (II) is connected to the wire 29, 15 and so on, in the direction of the arrow, Fig. 7, while the drum remains stationary, until the last boss 30 (X) has been attained. The first ten printing plates have now been printed or skipped, in conformity with the perforations in the respective rows. Upon the tenth partial rotation of shaft 8 by which the first scanning member 31 is cut in for the next cycle, the drum is entrained by the single-tooth gear 38, and the second row is presented to the scanning members 31. This is repeated until the strip has moved through the selector.
- 20 The described operation occurs if the switch 53 is in the full-lines position. When one of the scanning members 31 engages in a hole in the strip, the following circuit is established: from P through 29, 26, one of the bosses 30, the corresponding scanning member 31, drum 9, wire 34, switch 53, coil of control magnet St, machine switch 55 (automatically closed in time), and N. As described above, the plate 4 at the station is printed when the control magnet is excited and partly arrests the system B.

25 By connecting the switch 53 to the contacting point 58, the control magnet is excited when the scanning member does not encounter a hole, and de-energized when it does. Current flows from 56 to 58 through 57 and through the control magnet St when the scanning member does not encounter a hole. If it does, the circuit from P to 34 is established as described, but only as far as the shunt 34'. The relay 54 is excited 30 and attracts its armature, opening its switch 57, the control magnet St is not excited, and the plate at the station is not printed. This operation may be termed a "negative" selection, those printing plates which correspond to holes in the strip 48, being skipped.

35 The connection for checking the synchronous operation of the printing plates and the strip will now be described. The tenth boss 30 (X) is used for checking, and therefore every tenth printing plate must be equipped with means such as a projection, for closing the switch 63. It has been said above that the printing plates are not equipped with such means but this applies only to means for operating a multiple switch. If the printing plates and the strip move

in synchronism, the two resistances 60 and 64 whose ohmic values are equal, are cut in at the same time by the boss 30 (X) and the switch 63. The relay 65 is not excited, the two resistances 60 and 64 being connected to the relay 65 in the manner of a Wheatstone bridge, and the machine is not arrested. If the synchronism is disturbed, for instance, if the printing plates do not move through the machine in the proper sequence, one of the resistances 60 and 64 is not supplied with current, and the relay 65 is energized, arresting the machine. The operator will now remove the cause of the trouble, and restart the machine.

30 Instead of providing ten scanning members 31, as described, I may provide a single scanning member (not shown) which is moved intermittently with respect to the strip 48 and successively scans the rows of the strip.

35 Referring now to Figs. 8 and 9, these show the other type of selector, with a drum of insulating material, and a single scanning device. The device is a contact brush 68 which extends all over the width of the rows of the strip 48 and is connected to the positive wire P of the system by a wire 63. The barrel 9' of the drum which is shown flattened out in Fig. 9, is of insulating material, with a contacting strip 70, of helical shape, embedded therein. One end of the contacting strip is connected to a slip ring 71 and a wire 67 connects the ring to the negative wire N of the system.

40 The drum 9' is fixed on the shaft 8 which is mounted in the selector bracket 7, as described above, and the pins 12 are arranged on a pair of sprockets 72 at opposite ends of the drum 9' which are free to turn on shaft 8. The shaft 8 is rotated intermittently by means such as the lever 15, pawl 14 and ratchet wheel 13, and the sprockets are connected to the shaft by a pair of one-tooth gears 73, each with a tooth 73a, like the tooth 38b of the single-tooth gear 38. The gears 73 cooperate with two pinions 36 on the shaft 37, with short teeth 36a and elongated teeth 36b, as described, and the spur gears 35, as described above, the only differences being that the gears are duplicated and that they operate the sprockets 72 and not the drum, as in the first type. By these means the sprockets are entrained only after every tenth partial rotation of the drum 9'. 45

50 Fig. 9 shows a portion of the strip 48, with the rows of punching stations between lines 51 for 100 and 200. As the drum is here flattened out, its contact strip 70 shows as a straight line. The black spots in the rows of punching stations 55 indicate holes. The brush 68 makes contact through the holes of the several rows, closing the circuit through the brush and the contact strip 70, and through the members illustrated in Fig. 7. When a row has been scanned, i. e., when the drum 60 has performed as many—ten—partial revolutions in the direction of the arrow 74 in Fig. 9 as there are punching points in a row, the sprockets 72 are operated to present the next row to the brush 68 for scanning. The beginning of every row 65 which is thus presented, co-incides with the beginning of the contact strip 70.

55 I claim:

1. In an address-printing machine, a selector including a support of electrically conducting material, a fixed scanning device having a set of scanning members which are insulated with respect to each other, for making contact with said support, and means for moving a control strip past said support and said scanning members so 70

as to enable said members to make contact with said support through holes in said strip arranged in rows of as many punching points as there are scanning members in said set, transversely to the 5 sides of the strip; means for imparting intermittent movement to said strip-moving means from the printing mechanism of the machine in conformity with the pitch of the rows on the strip, a control magnet, a circuit connected to the support and to said magnet and adapted to be 10 made by one of said scanning members contacting with said support through one of the holes in said strip, and means for successively connecting the individual scanning members to said 15 circuit.

2. In an address-printing machine, a selector including a shaft, a drum of electrically conducting material which is free to turn on said shaft, a fixed scanning device having a set of scanning 20 members for making contact with said drum, means on said drum for moving a control strip past said drum and said scanning members so as to enable said members to make contact with said drum through holes in said strip arranged 25 in rows of as many punching points as there are scanning members in said set, transversely to the sides of the strip, and a contacting boss per scanning member, the contacting bosses being electrically connected to the corresponding scanning 30 members; means for imparting intermittent movement to said shaft from the printing mechanism of the machine, mechanism operatively connected to said shaft and to said drum for imparting intermittent movement to said drum in conformity with the pitch of the rows of the strip, a control magnet, a circuit connected to said drum and adapted to be made by one of said scanning members 35 contacting with said support through

one of the holes in said strip, and a contacting block, also connected to said circuit and adapted to rotate with said shaft, for successively engaging said contacting bosses.

3. In an address-printing machine, a selector including a support of electrically conducting material, a fixed scanning device having a set of scanning members for making contact with said support, and means for moving a control strip past said support and said scanning members so as to enable said members to make contact with said support through holes in said strip arranged in rows of as many punching points as there are scanning members in said set, transversely to the sides of the strip; means for imparting intermittent movement to said strip-moving means from the printing mechanism of the machine in conformity with the pitch of the rows on the strip, a control magnet, an electric system having a pair of conductors, a circuit connected to said 10 conductors, to the support, the scanning device and the magnet, and adapted to be made by one of said scanning members contacting with said support through one of the holes in said strip, another circuit, also connected to said conductors, for 15 checking the synchronous movement of the printing plates moving through the machine, and of said strip, said checking circuit being connected to one of said scanning members, a switch in said circuit adapted to be operated by selected printing plates, equal resistances in two branches of said checking circuit, and a relay connected to both said branches so as to be energized when said circuit is not closed by said switch simultaneously 20 with the making of contact by the scanning member which is connected to the checking circuit. 25

JOSEPH KRELL.
